United States Patent Office

Des. 201,757
Patented July 27, 1965

201,757

MIXER

Lawrence H. Wilson, Grosse Pointe, and Richard E. Watson, Detroit, Mich., assignors to Sunbeam Corporation, Chicago, Ill., a corporation of Illinois

Filed Jan. 7, 1965, Ser. No. 83,324

Term of patent 14 years

(Cl. D44—1)

Fig. 4.

Fig. 5.

Fig. 6.

Fig. 7.

FIG. 1 is a perspective view of a mixer embodying the design;

FIG. 2 is an enlarged front view thereof;

FIG. 3 is a top view thereof;

FIG. 4 is a side view thereof;

FIG. 5 is a rear view thereof;

FIG. 6 is an enlarged fragmentary sectional view taken along the section line 6-6 of FIG. 2; and

FIG. 7 is an enlarged fragmentary sectional view taken along the section line 7-7 of FIG. 5.

The dominant features of the design reside in those portions shown in full lines.

We claim:

The ornamental design for a mixer, as shown and described.
